UNITED STATES PATENT OFFICE.

HOMER LEROY PHELPS, OF ATHENS, PENNSYLVANIA.

ROTARY STEAM-ENGINE.

SPECIFICATION forming part of Letters Patent No. 404,557, dated June 4, 1889.

Application filed August 6, 1888. Serial No. 282,083. (No model.)

To all whom it may concern:

Be it known that I, HOMER LEROY PHELPS, a citizen of the United States, residing at Athens, in the county of Bradford and State 5 of Pennsylvania, have invented certain new and useful Improvements in Rotary Steam-Engines; and I do hereby declare the following to be a full, clear, and exact description of the invention, which will enable others skilled in the art to which it appertains to 10 make and use the same.

My invention relates to various new and useful improvements in rotary steam-engines, mainly consisting in a peculiar eccentric piston 15 driven by steam admitted and controlled by valves of peculiar construction, in conjunction with suitable inlet and outlet ports, and in the novel operative combinations of the various parts.

20 The prime object of my invention is to effect the saving of steam, and I accomplish this by a peculiar construction of the piston and its working parts, and of the said valves, thus enabling me to use the steam expans- 25 sively to a great extent, by means of which the amount of steam used is about one-third less than is ordinarily the case.

In order to enable those skilled in the art 30 to comprehend my invention, attention is directed to the following views, in which like letters refer to corresponding parts in the several drawings.

Figure 1 is a central cross-section of the engine. Fig. 2 is a longitudinal cross-section, 35 and Fig. 3 is a perspective view of the valve.

In the drawings, let A designate the cylinder, and B B' the cylinder-heads, one or both cast with the cylinder or fastened to the cylinder in any suitable manner to render the 40 cylinder steam-tight, or by which it may be packed steam-tight. Within this cylinder and passing directly through the center of the same, and continuing centrally through the cylinder-heads B B', is the shaft C. To 45 this shaft C is eccentrically secured a piston, D. This piston is made in two sections a and b. The larger part a, through which passes the shaft C, has a tongue a', of its entire width, which is adapted to enter a groove b' 50 in the smaller section b of the piston and thus hold the same firmly. This section b,

when in position on the tongue a', should fit nicely against the cylinder A and the heads B B, so as to form practically a steam-tight joint between them. Said piston D is so arranged upon the shaft C that the portion b 55 just comes into contact with the body of the cylinder at the point c. The reason for having this division of the piston is that when the part b becomes worn by contact at c with 60 the inner surface of the cylinder-wall it can be caused to move on the tongue a' toward the wall of the cylinder in any convenient way, and thus always meet said wall at the point c on the downstroke and at an opposite point 65 c' just as the piston begins the upstroke.

Beyond the openings d d', which are used for the introduction of steam, is the double steam-chest e e'. Within each of these chests, respectively, are the valves E E', so arranged 70 that when the steam enters or leaves the cylinder it carries said valves with it until its progress is arrested by the projections e² e³ inside of the openings d d', or the piston, as the case may be. The openings F F' give 75 communication of the steam-chests e e' with the interior of the cylinder A. Between these steam-chests is a partition H, separating the live from the exhaust steam. Above and below the said chests are situated the two ex- 80 haust chambers or ports G G'.

The construction of the valves E E' is as follows: Each are alike in form and action; hence a description of one will suffice for both. Each consists of a flat body f, at the forward 85 portion of which is a projection f', made integral therewith, extending upward at an angle of nearly thirty degrees and somewhat thicker than the body f. Extending forward and on each side of this projection are two other 90 short projections g g'. The inside distance between these two latter projections is slightly greater than the width of the part a of the piston. The side surfaces f² and f³ of the body f are at a somewhat less angle than 95 forty-five degrees, (though that is not necessary,) to enable the valve to keep in the track h or h' of the steam-chest e or e', so that when pushed forward by the onward rush of the steam it will not overbalance itself when 100 through the openings F or F' and fall into the cylinder.

In case it should be desired to reverse the motion of the engine the steam, instead of entering the port d , is caused by suitable means to enter at d' , and in this case it exits 5 at G instead of G' ; otherwise the operation is the same.

The operation is as follows: Steam comes from the boiler through suitable pipes and enters the port d , passing through the valve- 10 chest e in the meantime, pushing the valve E with it, and, when the projection f' of said valve passes the opening F , rushes forward and into the cylinder, where it presses against the sides of the tongue b of the piston until 15 said piston revolves on its shaft C . After the piston makes about two-thirds of a revolution the valve E is pressed back by the presentation of the larger side of the piston and the projection f fills the opening F , thus cutting off the supply of steam for the time being and allowing that in the cylinder to act 20 expansively. As the piston is still being pushed forward by the steam, the former live steam becoming exhausted passes into the 25 chamber G' and from thence into the open air; but while the latter is occurring the portion b of the piston has passed the valve E , which is gradually pressed onward by the steam behind it until the piston arrests its 30 passage, whereupon the steam enters the cylinder as before and goes through the same operation. When the valve E is in use the

other one E' covers the opening d' . A reverse motion is given to the portion, as before mentioned, by admitting steam on the other 35 side of the partition H .

Having now described my invention, what I claim as new, and desire to secure by Letters Patent, is—

1. In a rotary engine of the character described, the combination of the cylinder, a piston mounted eccentrically on a shaft passing through the same, a valve-chest at one side of said cylinder, the chambers G G' , connected with said cylinder, separated from each 45 other by a partition, and the valves E E' , one in each chamber, substantially as and for the purposes set forth.

2. In a rotary engine, a sliding valve E , consisting of a flat body f , front a , projection f' , 50 and side projections g g' , substantially as described.

3. In a rotary engine, the combination, with the piston made in two parts mounted eccentrically on a shaft, of the valves E E' , working in conjunction with said piston and bearing in the tracks h h' , substantially as described. 55

In testimony whereof I affix my signature in presence of two witnesses.

HOMER LEROY PHELPS.
